UNITED STATES PATENT OFFICE.

PHILEMON O. DICKINSON AND OTTO LEIGH, OF NEWARK, NEW JERSEY.

DESIGN FOR A BACK FOR BRUSHES OR SIMILAR ARTICLES.

SPECIFICATION forming part of Design No. 36,223, dated February 10, 1903.

Application filed October 29, 1902. Serial No. 129,336. Term of patent 3½ years.

To all whom it may concern:

Be it known that we, PHILEMON O. DICKINSON and OTTO LEIGH, citizens of the United States, residing at Newark, county of Essex, State of New Jersey, have invented a new, original, and ornamental Design for the Back of a Brush or Similar Article, of which the following is a specification, reference being had to the drawing accompanying and forming part of the same.

As shown in the drawing, the leading or material features of our design are strands or ribbons 1, following the general outline of the back, folded or convoluted at opposite ends of the back, and holding bunches of flowers in such folds or convolutions.

In the particular embodiment illustrated the article to which the design is applied is

provided with a handle 2. In such case the strands or ribbons 1 extend along the same 20 and inclose, near the end thereof, another group of flowers. The center space shows the head and shoulders of a female figure holding in one hand a daisy from which the other is plucking a petal. The background is formed 25 by coils and tresses of the figure's hair.

Having now described our invention, what we claim is—

The ornamental design for the back of a brush or similar article, as herein shown and 30 described.

PHILEMON O. DICKINSON.
OTTO LEIGH.
